ENCLOSED ARC DEVICE

Frederick Weinberg, Detroit, Mich.

Application June 7, 1926. Serial No. 114,166

10 Claims. (Cl. 176—123)

My invention relates to an improved electric light. It pertains particularly to improvements in electric arc lights wherein the arc is located within a sealed container.

5 The object is to provide an improved arc light of this character which possesses unusually high efficiency and long life and which is completely self-contained in that it will almost instantly respond upon the closing of the control switch in 10 the current supply circuit and without the aid of auxiliary starting devices of any kind.

My improved light is so constructed that it may be disposed at any angle. It is adaptable for use within the ordinary light sockets. It operates 15 upon light current of conventional voltage and it responds to the same current for starting.

Other important and material objects and advantages will more fully appear from the following description, appended claims and accompanying drawing which illustrates one embodiment of my invention and in which:

Figure 1 is a vertical sectional view through my improved electric arc light.

Fig. 2 is a vertical sectional view taken at right angles to the view in Fig. 1.

Fig. 3 is a horizontal sectional view taken on line 3—3, Fig. 1.

The container or glass bulb is indicated as 10. This bulb carries a threaded end 12 adapted to 30 be received within the conventional light socket. The bulb has been exhausted of air and filled with a suitable inert gas, such as argon neon helium or a mixture of these gases. It is provided with contacts 14 and 16. A pair of spaced-35 apart electrodes 18 and 20 formed of a suitable refractory material are mounted within the bulb. Electrode 18 leads into the bulb from contact 14 and terminates in a ball end 22. Electrode 20 leads into the bulb from contact 16 and terminates in a ball end 24. These ball ends are disposed in 40 opposed relationship and spaced apart to form a gap 25, which gap may vary in magnitude but is relatively small. The ball ends of the electrodes are formed of a material having a substantially 45 high melting point, such as tungsten or certain oxides or materials.

After leaving the contacts the two electrodes approach each other relatively closely. From this 50 point of comparative proximity they diverge to a point adjacent to their tips, from which point the extreme tips converge to the opposed relationship illustrated at the gap 25. The magnitude of this gap 25 is here shown as greater than 55 the distance which separates the electrodes at

the aforementioned point of comparative proximity.

This point of closest approach of the two electrodes is surrounded by an enclosure or cage 26 spaced from the electrodes. This cage may be 60 supported either by the electrodes themselves or by the container, as shown in the drawing.

The cage is formed of suitable heat, light and electric insulating material. Within the cage and within the field of the electrodes I place suitable 65 material of the alkali metal group such as potassium or sodium. This material is of such a character as to facilitate ionization of the gas space within the cage and particularly in the interval between the electrodes. This alkali metal material 70 is deposited on the wall of the cage or amalgamated as with tin or mercury to form plates 28 and 30. Plate 28 is connected with electrode 18 and plate 30 is connected with electrode 20. These plates 28 and 30 are insulated from each 75 other.

After leaving the cage the electrodes are bent in such a manner that the arcing gap 25 is out of line with the interior of the cage 26. One reason for thus positioning this arcing gap is 80 to avoid the deleterious photoelectric effect the arc would have on the alkali metal disposed within the cage. Otherwise the arc would so affect the alkali metal as to encourage loss of electrons and the deteriorating, tiring effect of 85 the metal would materially reduce its capacity to initiate the formation of the arc. Therefore, I protect the alkali metal within the shadow of the cage. The presence of the cage prevents the diffusion of the alkali electrons thereby adding 90 greatly to the efficient bombardment of the gas atoms within.

The action of my light is as follows: The bulb being inserted in an ordinary light socket and the control switch turned on, a current of the 95 usual character of approximately 110 volts potential, which may be either alternating or direct current, enters the electrodes. The extent of the gap 25 is too great to permit ionization of the gas space between the ball ends of the electrodes which would encourage arcing at such point but within the cage the field formed by the current in the electrodes pulls the loosely bound valence electrons out of the alkali metal and they bombard the electrons of the inert gas atoms, 105 thereby dislodging them to the ionization level of the atom and producing a state of ionization of the gas between the electrodes which results in the formation of an electric discharge at this 110 point.

Due to the direction of the magnetic field surrounding the electrodes this electric discharge is driven outwardly along the electrodes until it reaches the gap 25. It bridges this gap and forms an arc at such point. The magnetic field at the gap is not antagonistic to the maintenance of a stable arc because of the opposed relationship of the balls and because of the offset position of the gap with reference to the electrodes, and 10 the arc, therefore, remains constant at this point until the current is turned off.

This gap 25 is preferably positioned in the center of the bulb so that as little heat as possible is lost to the wall of the bulb and also in 15 order that the evaporation of the atoms at the ends of the electrodes is as far removed as possible from the wall of the bulb, thereby minimizing the deposit of blackening matter on said wall.

Upon the establishment of the arc at the gap 20 25 there is a drop in voltage at the electrodes which decreases the strength of the electric field between the plates and as a result few, if any, electrons are pulled out of the alkali metal, thereby inhibiting the formation of an arc inside the cage during the persistence of the arc 25 at the gap 25.

The electrodes should possess sufficient resistance to choke the current and I accomplish this by providing ball ends formed of tungsten, 30 cerium, suitable oxides or other similar materials which possess high electric as well as heat resisting capacity. Otherwise some artificial resistance should be shunted into the circuit at a convenient point and preferably where it might 35 serve a number of lights.

What I claim is:

1. The combination in an electric light, of spaced-apart co-operating electrodes mounted within a sealed container separated at their tips 40 by a gap of greater magnitude than at a point remote therefrom and having material of the alkali metal group associated therewith at such remote point of less magnitude responsive to a light current of conventional voltage to induce 45 a discharge at such point which is driven outwardly by the magnetic influence of the current through the electrodes and established at the tips thereof.

2. The combination in an electric light, of spaced-apart co-operating electrodes mounted within a sealed container separated at their tips by a gap of greater magnitude than at a point remote therefrom and having material of the alkali metal group connected with one of said electrodes at such remote point of less magnitude whereby a discharge is established at such point responsive to the magnetic influence of the current through the electrodes to travel outwardly to their tips.

60 3. The combination in an electric light, of spaced-apart co-operating electrodes mounted within a sealed container separated at their tips by a gap of greater magnitude than at a point remote therefrom and having associated therewith at such remote point of less magnitude a deposit of alkali metal connected with each electrode, said deposits being insulated from each other and adapted to produce ionization of the gas between the electrodes to establish a discharge 65 at such point responsive to the current through the electrodes to be driven outwardly to the tips.

70 4. The combination in an electric light, of spaced-apart co-operating electrodes mounted

within a sealed container and having tip portions separated by a gap of greater magnitude than the distance which separates the electrodes at a determined point remote from their tips, a cage about said electrodes at such remote point of less magnitude, and an alkali metal deposit carried by said cage to facilitate initial discharging between the electrodes at such point responsive to the current through the electrodes to be driven outwardly to their tips. 80

5. An electric arc light, comprising a sealed container filled with an inert gas, electrodes mounted therein having current connections and provided with opposed tips separated by a gap for arcing, said gap being of greater magnitude than the distance between said electrodes at a point remote from the gap, a cage of insulating material about said electrodes at such remote point of less magnitude, and material of the alkali metal group separated into two insulated patches one connected with one electrode and the other connected with the other electrode responsive to the conventional light current to establish temporarily a discharge at such point subject to the current through the electrodes to travel outwardly 95 thereover to their tips.

6. An electric arc light provided with electrodes separated at their tips by a gap for arcing and characterized by the provision of a cage about the electrodes at a point remote from their 105 tips, and material within said cage responsive to the conventional low voltage light current to facilitate initial arcing between the electrodes within the cage, the arc being responsive to the current through the electrodes to travel outwardly 110 to their tips.

7. The combination in an electric light, of spaced apart cooperating electrodes mounted within a sealed gas-filled container, said electrodes provided with current connections and 115 separated at their tips, a material disposed in proximity to the electrodes at a point remote from their tips responsive to the conventional light current to facilitate ionization of the gas between the electrodes to establish a discharge 120 at such point responsive to the current through the electrodes to be driven outwardly to their tips, and means to protect said material from the influence of the actinic arc rays.

8. An electric arc light provided with spaced 125 apart electrodes separated at their tips by a gap for arcing and provided with a cage about the electrodes at a point remote from their tips, material within the cage adapted to facilitate ionization of gas between the electrodes and responsive 130 to the normal low voltage light current to establish temporarily an electric discharge at such point responsive to the current through the electrodes to travel outwardly to produce a permanent arc at their tips, said tips extending beyond said cage and being offset with respect 135 to their point of outlet from the cage.

9. An electric arc light including a gas filled container enclosing a material to initiate an electric discharge, electrodes in said container and means to shield said material from the rays of 140 the discharge to avoid deterioration.

10. An electric arc light provided with electrodes separated at their tips by a gap for arcing and characterized by the provision of a cage about 145 the electrodes at their lower ends only and material within said cage to facilitate a discharge between the electrodes.

FREDERICK WEINBERG.
